(No Model.)

M. MILLHAUSER.

AUTOMATIC SWITCH.

No. 366,786.

Patented July 19, 1887.

UNITED STATES PATENT OFFICE.

MOSES MILLHAUSER, OF NEW YORK, N. Y.

AUTOMATIC SWITCH.

SPECIFICATION forming part of Letters Patent No. 366,786, dated July 19, 1887.

Application filed February 10, 1887. Serial No. 227,167. (No model.)

To all whom it may concern:

Be it known that I, MOSES MILLHAUSER, a citizen of the United States, residing at New York city, in the county of New York and 5 State of New York, have invented certain new and useful Improvements in Automatic Switches; and I do hereby declare the following to be a full, clear, and exact description of the invention, such as will enable others to skilled in the art to which it appertains to make and use the same.

This invention relates to automatic switches for railroads; and it consists in the novel construction and arrangement of parts, as will be 15 hereinafter described, and particularly pointed out in the claims.

In the accompanying drawings, Figure 1 is a plan view of the switch. Fig. 2 is a cross-section showing the means for operating the 20 switch, and Fig. 3 is a longitudinal section of the same.

Referring to the drawings, the letters A and A' designate the sections of the main rails of the track, which are secured to ordinary sleepers 25 or ties, *a*, in the usual manner.

A³ denotes the switch-rails, which are secured at the end next to the section A to the sleepers of the rails of the section A'. The section A is provided at its end with an intermediate section, A², the rails of which are pivoted to the end of the rails of said section A by means of pins *b*, or in any other suitable manner, to form hinge-joints with said rails of section A, and are adapted to connect with 30 either the rails of section A' or switch-section A³, as may be desired. The intermediate section has connected to its middle portion, on its under side, a bar, B, which has connected to it a plate, C, which is pivoted at one end to one 35 of the sleepers, as shown, by means of a pin or bolt, *c*. The plate C has formed on its upper surface a double cam, C', for a purpose hereinafter explained. To one of the sleepers, as shown in Fig. 1, and abutting on the out- 40 side of the section A', and which projects beyond the ends thereof, are secured stops *d*, which prevent the free ends of the intermediate section, A², from passing out of line with the ends of the rails of the section A'. 45 The bar B slides on a block, F, and is pivoted to the plate C, being located in a recess or

groove on the under side of said plate, the said groove being of greater width than that of the bar, so as to permit the free action of said bar when moved.

The letter D represents the truck of a locomotive or car, having at its front end brackets *d'*, provided with openings in which the vertical spring rods or shafts *f f'* are located, said shafts having on their lower ends disks *f² f³*, 50 while the upper ends of these shafts have removably connected to them levers *g g'*, which are connected to upright standards *e e'*, by means of which the disks are thrown into or out of engagement with the double cam C' on either side thereof, whereby the intermediate section, A², can be shifted to the right or left, as may be required, to connect with the switch-rails A³ or main rails A A'.

The manner of operation is as follows: A 70 car being on the main section A and traveling in the direction of the arrow E, if it is desired to run the same on the switch-section A³, the rod *f* is depressed, so that the disk *f²* is brought in contact with the side of the cam C', whereby 75 the intermediate section, A², is swung so that the rails thereof connect with the rails of the section A³ and the car runs upon the switch, leaving the main-rail sections open. If a second car coming in the same direction is de- 80 sired to run on the main section A', the disk *f³* is depressed and the intermediate section, A², is swung so that the rails thereof connect with the rails of said section A', and the car then runs on the said rails. When, however, 85 after a car has been run on the switch and another car is on the main section A', and is going in the direction of the arrow E', and it is desired to continue it on the main section A, the disk *f²* of said second car is depressed 90 and brought into contact with the cam, so that the rails of the intermediate section are swung into connection with the rails of said main section A', whereby the main line is intact and the car can move thereon.

I am aware that it is not new to construct an automatic switch the rails of which are hinged to the main rail; neither is it new to provide said movable section with cams, whereby the same can be operated by means attached 100 to the car, and such I do not claim; but I am not aware that it is old to construct a switch,

as herein described, wherein the intermediate portion is hinged to the same sleeper as the rails, nor where the stops are secured as herein described.

5 What I claim is—

1. In an automatic switch, the vertically-movable spring-rods f, f' , having disks f^2, f^2 at their lower ends, and provided with levers or handles pivoted in standards to the truck of a car or locomotive, in combination with the intermediate rail section, A^2 , and an operating-lever having double cam C' , all substantially as shown and described.
2. In an automatic switch, the main sections 15 A and A' , the intermediate section, A^2 , forming part of the main track, and having its rails hinged to the rails of section A , the switch-section A^3 , the bar B , the plate C , hinged to the sleeper on which the rails of A^2 and A are

hinged together, and pivoted to bar B , and 20 having a recess on its under side, substantially as described, and the double cam C' , all combined and arranged to operate substantially as described and set forth.

3. In an automatic switch, the combination, 25 with the main-rail sections, the switch-sections, and the intermediate sections pivoted to one of the main sections, of an operating-bar pivoted to said intermediate sections, having a double cam-plate with recessed undersurface, as shown 30 and described, and for the purpose set forth.

In testimony whereof I affix my signature in presence of two witnesses.

MOSES MILLHAUSER.

Witnesses:

SAMUEL ULLMAN,
JAMES R. LOANE.
